ROBERT HERZOG, OF BERLIN, GERMANY, ASSIGNOR TO C. LORENZ AKTIENGESELLSCHAFT, OF LORENSWEG-BERLIN-TEMPELHOF, GERMANY.

MEANS FOR PRODUCING ELECTRIC OSCILLATIONS BY AN ELECTRIC ARC.

Application filed July 12, 1920. Serial No. 395,810.

To all whom it may concern:

Be it known that I, ROBERT HERZOG, residing at Berlin, Germany, have invented certain new and useful Improvements in Means 5 for Producing Electric Oscillations by an Electric Arc, for which I have filed applications in Germany, June 5, 1918; Holland, Aug. 8, 1919; Denmark, Aug. 9, 1919; Norway, Aug. 18, 1919; Sweden, Aug. 28, 1919; 10 England, Sept. 16, 1919; and in France, Oct. 14, 1919, of which the following is a specification.

In the method of producing oscillations by means of the electric arc irregularities in the 15 burning of the electric arc often occur because it is practically impossible to keep the conditions to which the arc is subjected completely constant and small differences in the substance of the electrodes are sufficient to 20 cause changes of wave length. Although these changes are so small that the fluctuations of energy are not noticeable whilst receiving they are nevertheless exceedingly troublesome because in receiving waves with 25 surging amplitudes the changes of wave lengths result in variations of the tone pitch and, instead of a simple tone, a twittering note results because in the measure in which the wave length changes, trains of higher 30 and lower tones arise in alternate succession.

This invention relates to a method of obtaining an extraordinarily uniform burning of the electric arc with the aid of a self-induction, this self-induction being connected 35 in series with the arc and made very large. A capacity whose magnitude lies outside the range of the tuning must evidently be inserted in a circuit comprising the light arc and the two self-induction coils, in order to 40 avoid short-circuiting of the continuous current. Another result obtained by this method consists in an appreciable increase of the efficiency of the light arcs now employed.

The invention is illustrated in the drawing in which:—

Figure 1 shows a form of circuit employed.

Figure 2 illustrates a circuit in which a coupling of the self-induction with aerial is 50 avoided and

Figures 3 and 4 show further modifications of the circuit.

A self-induction s^1 , Figure 1, of comparatively large size is connected in series with the electric arc s^1 and an electromagnetic field of similar magnitude is connected in parallel to the self-induction s^1 and the arc. In order to avoid short-circuiting of the continuous current a capacity c is further provided whose magnitude does not influence the oscillation and is consequently not critical beyond a determined value. With all currents which flow parallel through these self-inductions s^1 and s^2 , the total self induction is reduced and it can be reduced to a very small figure if the two fields are intimately coupled with each other. For all currents, which pass through the two self-inductions in series the full value of these self-inductions comes however in question.

The result of this arrangement is that, within very wide limits, the extinguishing or even the irregular burning of the arc is prevented because as soon as the fields in the two branch paths become unequal a high tension of the self-induction immediately arises at the electric arc and renders harmless any resistance which may be offered by the arc. It is therefore possible to adapt without any difficulty the light arc to such a gap between the electrodes that a much higher value of current is obtained in the oscillating system (antenna A) than the continuous current supplied, so that the efficiency is increased to a multiple of that attained in the type of circuit hitherto employed. The independence of the arc is so marked that it is possible to change the polarity of the continuous current at the electrodes without any deleterious effect.

An essential feature of the invention is that directly at the high frequency side of the light arc lies a self-induction, which is as large as possible, for the purpose of governing the arc. But this large self-induction s^1 shall enter into action only when irregularities occur in the arc and it shall be as ineffective as possible when the oscillations passing in the antenna circuit are regular so as to enable waves of comparatively very

small length to be produced in spite of the large self-induction.

In order to avoid currents flowing in series through the self-induction during regular working the circuit formed by these self-inductions should, if possible, not be coupled with the aerial. This may be most simply accomplished by making according to the form of construction shown by Fig. 2 the 10 two self-inductances (s^1 , s^2) in Fig. 2 of equal size. Since the condenser c , which is connected in series with these inductances so as to prevent short-circuiting of the arc, must also be made very large, the circuit s^1 , 15 s^2 , c and l will be uncoupled from the oscillating circuit. The former circuit, which includes the two coils s^1 , s^2 in series, is not to be regarded as an oscillatory circuit for currents of high frequencies because its 20 wave length is much larger than that of the high frequency circuit and oscillations of this circuit cannot be actually ascertained in the same.

The values of the self-inductances vary in 25 series of magnitudes up to millions of centimeters as otherwise no uniform burning of the arc will be attained. The governing of the arc is the better the larger is the value of induction of the coil that is connected to 30 the arc, and the only consideration that confines practically the size of this self-inductance of the coil at the arc, is that the inductance of the coil connected to the arc cannot be completely neutralized by the field of 35 the inductance connected in parallel with it and hence a certain balance remains which prevents the wave length of the oscillatory circuit from being reduced to the desired small value. Another consideration is that 40 the inductances themselves cannot be constructed so as to be free from losses and that if the self inductance were made too large the advantages consisting in an increased output of energy would be nullified 45 by losses due to ohmic resistance.

Other forms of circuit for producing electric oscillations in accordance with the invention are illustrated in Figs. 3 and 4, according to which as tight a coupling of 50 the light arc with the antenna as possible is produced by a transformer with the most favorable ratio of transmission, the capacity c being also merely a block condenser for the continuous current and the current circuit c , s^1 at the light arc l being no oscillating circuit. Coil s^1 is lying in the field of coil s^2 , which field is preferably of similar size as the self inductance s^1 . The primary windings are normally greater in number 55 than the secondary windings (in the antenna) so that the antenna current produces high voltages in the light arc when disturbances occur in this arc, in a similar manner as is the case in the connection 60 shown by Figs. 1 and 2. As the transformer 65

is as strayless as possible the effect of its self-inductance disappears almost completely at the normal working so that, in a similar manner as in Figs. 1 and 2, an effect is inappreciably produced which tends to 70 lengthen the waves. The arc l is included in the circuit c , S^1 , the coil s^1 lying in the field of the coil s^2 which is connected in series with the multiple paths constituted by the arc l and the coil s^1 .

Figure 4 shows an arrangement in which the aerial circuit A is coupled as closely as possible with the general circuit l , c , S^1 , so that s^1 and s^2 represent the windings of a transformer without iron. The connection shown by Figure 4 fulfills also the condition that a high self inductance be used at the high frequency side of the electric arc in a circuit which does not oscillate independently, as the self inductance which results in Fig. 4 from the two coils S^1 and S for the system is dependent on the coupling of the two coils and on the strength of current of the two circuits l , c , S^1 and A , S earth and of the phase displacement of the same.

If, for instance, the coupling of the two coils is straylessly tight, if the strength of current of the two circuits is inversely proportional to the numbers of windings of the two coils and if the phase displacement of the coils in the two circuits—with corresponding direction of winding—differs by 180° , or if, with another direction of winding of the coils, no phase displacement of the two currents exists, the resulting field of the two coils will be zero and the self inductance will have no influence on the tuning. Although this effect can be considered merely as a limiting case, it is possible to come near the same by an appropriate construction, to ascertain that no independent vibration occurs in the circuit with the higher self-inductance. Herefrom follows, that also the connection shown by Fig. 4 with the characteristic feature of the main claim attains the effect aimed at.

I claim:

1. An improved connection for the production of electric oscillations with the aid of the light arc, comprising in combination with the oscillatory antenna circuit and with the light arc, a circuit which does not oscillate independently situated on the high frequency side of said light arc between the arc and the oscillating circuit, a large self-inductance in said circuit, and a second self-inductance coupled with said first self inductance in such a manner that the effect of said first self inductance upon the oscillatory antenna circuit is entirely or nearly neutralized.

2. An improved connection for the production of electric oscillations with the aid of the light arc, comprising in combination with the oscillatory antenna circuit and with

the light arc, a circuit which does not oscillate independently situated on the high frequency side of said light arc between the arc and the oscillating circuit, a large self-inductance in said circuit, and a second self-inductance connected in parallel with said first self inductance and said light arc in such a manner that the effect of said first self inductance upon the oscillatory an-

tenna circuit is entirely or nearly neutralized. 10

In testimony whereof I have signed this specification in the presence of two witnesses.

ROBERT HERZOG.
